SAFETY BELT

Raymond E. Dowd, Chicago, Ill.

Application August 17, 1943, Serial No. 499,021

3 Claims. (Cl. 227—49)

This invention relates to improvements in safety-belts.

One object of this invention is to provide an improved safety-belt having a quick-release buckle which can be readily adjusted on the belt to bring it in a central position with regard to the person wearing the belt.

Another object of this invention is to provide an improved safety-belt having a quick-release buckle and means for providing adjustment for the strap near the quick-release buckle and minimizing wear on the strap.

With the above and other objects in view, as will appear to those skilled in the art from the present disclosure, this invention includes all features in the said disclosure which are novel over the prior art.

In the description and claims, the various parts and steps are identified by specific names for convenience, but they are intended to be as generic in their application as the prior art will permit.

In the accompanying drawings, in which one way of carrying out the present invention is shown for illustrative purposes:

Fig. 1 is a front elevation of a safety-belt made in accordance with the present invention;

Fig. 2 is a view similar to Fig. 1 on an enlarged scale, of the central portion of Fig. 1;

Fig. 3 is a front edge view of Fig. 2;

Fig. 4 is a sectional view on line 4—4 of Fig. 2, illustrating the quick-release buckle in its released or open position; and

Fig. 5 is a perspective view of one of the fixed buckle-members forming part of the present invention.

Referring to the drawings showing the particular form of the invention chosen for illustration therein, the safety-belt 10 includes a quick-release buckle 11 having a locking-lever 12 provided with an operating handle 13 and locking hook ends 14, the hook ends 14 being pivoted at 15 to hook ends or portions 16 of a link 17 similar to the hook ends or portions 14 of the locking-lever 12. A link 18 has a locking-bar portion 19 adapted to be engaged by the hook portions 14 and 16 when in locking position, as illustrated in Fig. 3.

The link 17 has a crossbar 20 pivotally mounted in an eye-bar 21 of a buckle-member 22. The buckle-member 22 also has two crossbars 23 and 24 parallel to each other and spaced from each other by a space 25. The crossbars 23 and 24 are also parallel to the eye-bar 21 and spaced therefrom by a space 26 as best shown in Fig. 5.

The link 18 has a crossbar 27 which is pivotally

mounted in the eye-bar 21 of buckle-member 28 which is identical with the buckle-member 22.

A strap-member 29 is secured to the buckle-member 22 by passing a portion up through the opening or slot 25, over the crossbar 23 down through the slot or opening 26, around the eye-bar 21, over the strap-portion in contact with the top of the crossbar 23, and down through the slot 25 between the crossbar 24 and the first described strap-portion extending up through the slot 25. This causes any pull upon the strap 29 to push the portion of the strap end 30 between it and the crossbar 24 up against the edge of the crossbar 24 and thus lock the strap 29 against coming out of its adjusted positions in the buckle-member 22. A stop-rivet 31 mounted in the end 30 of the strap 29 prevents the end 30 of the strap containing the rivet 31 from passing through the slot 25. The rivet 31 also serves to hold the U-shaped sheet-metal tip 32 onto the end of the belt with its opposite sheet-metal portions clamped against the opposite faces of the strap.

Inasmuch as the link 17 has its crossbar 20 pivoted within the eye-bar 21 of the buckle 22, all pivotal action between the members 17 and 22 takes place between the elements 20 and 21, and thus avoids any rubbing or wearing action upon the strap-member 29 with absence of consequent wear on the latter. A strap or strap-member 33 similar to strap-member 29, is similarly connected to the buckle-member 28.

All buckles and links of the belt shown in the drawings are preferably made of metal and may be made of steel preferably having a rust-proof coating thereon. The strap-members 29 and 33 are of flexible material, such for example, as woven fabric.

A loose tuck-loop 34 (Figs. 1 and 2) may be mounted adjacent each of the buckles 22 and 28 to hold the free upper ends of the straps close to the main portion of the straps. The extreme end of each strap may be formed into a return-loop 35 having a portion stitched down as at 36 and the loop 35 may carry a metal or other loop-member 37 therein.

The loop-members 37 at the opposite ends of the belt may be connected to any suitable location such as parts adjacent of a seat of a vehicle, 50 such for example as artillery, aircraft, etc., in which a person is sitting with the belt passing in front of him.

Where the opposite ends of the belt-straps 29 and 33 are connected to fixed locations by loop-members 37 or the like, the present construction

permits of shifting the adjusted positions of the straps in the buckles 22 and 28 to bring the quick-release buckle 11 centrally of the person wearing the belt, to bring the buckle into the best position for quick release by the person wearing it.

The invention may be carried out in other specific ways than that herein set forth without departing from the spirit and essential characteristics of the invention, and the present embodiment is, therefore, to be considered in all respects as illustrative and not restrictive, and all changes coming within the meaning and equivalency range of the appended claims are intended to be embraced therein.

I claim:

1. A safety-belt, including: two links detachably connected together, and each link having a cross-bar; two buckle-members each having an eye-bar surrounding and pivoted to a said cross-bar, and two cross-bars rigid with said eye-bar and spaced from said eye-bar and from each other; and two flexible straps, each adjustably connected to a said buckle by extending through the space between the said two cross-bars, over the cross-bar nearest said eye-bar, through the space between said eye-bar and said nearest cross-bar, over said eye-bar, and through the space between said two cross-bars and between the cross-bar most distant from said eye-bar and the first-mentioned strap-portion which extends through the space between said two cross-bars.

2. A safety-belt, including: a link having a

cross-bar; a buckle-member having an eye-bar surrounding and pivoted to said cross-bar, and two cross-bars rigid with said eye-bar and spaced from said eye-bar and from each other; and a flexible strap adjustably connected to said buckle by extending through the space between the said two cross-bars, over the cross-bar nearest said eye-bar, through the space between said eye-bar and said nearest cross-bar, over said eye-bar, and through the space between said two cross-bars and between the cross-bar most distant from said eye-bar and the first-mentioned strap-portion which extends through the space between said two cross-bars.

3. A safety-belt, including: a link having a cross-bar; a buckle-member having an eye-bar surrounding and pivoted to said cross-bar, and two cross-bars rigid with said eye-bar and spaced from said eye-bar and from each other; and a flexible strap having a load-end and a free-end and adjustably connected to said buckle by having its load-end extending through the space between the said two cross-bars, over the cross-bar nearest said eye-bar, through the space between said eye-bar and said nearest cross-bar and over said eye-bar, and having its free-end extending through the space between said two cross-bars and between the cross-bar most distant from said eye-bar and the portion of the load-end which extends through the space between said two cross-bars.

RAYMOND E. DOWD.
